UNITED STATES PATENT OFFICE.

BASIL L. FOGLE, OF BOYD, KENTUCKY.

FOLDING HAMMOCK-FRAME.

1,106,293.

Specification of Letters Patent. Patented Aug. 4, 1914.

Application filed February 16, 1914. Serial No. 818,983.

To all whom it may concern:

Be it known that I, BASIL L. FOGLE, a citizen of the United States, residing at Boyd, in the county of Harrison and State of Kentucky, have invented certain new and useful Improvements in Folding Hammock-Frames; and I do hereby declare the following to be a full, clear, and exact description of the invention, such as will enable others skilled in the art to which it appertains to make and use the same.

This invention relates to folding hammock supports or frames, and one of the principal objects of the invention is to provide a frame for supporting a hammock, which can be quickly set up for use, and when not required for use, may be folded within a small space for storage until it is again required.

Another object of the invention is to provide a supporting frame for a hammock, which shall be simple in construction and which can be quickly set up and folded, when not required for use.

These and other objects may be attained by means of the construction illustrated in the accompanying drawings, in which—

Figure 1 is a side elevation of the hammock supporting frame made in accordance with this invention, portions of the connecting bar members being broken away and showing a hammock broken away in the center, Fig. 2 is an end view of one of the supporting elements, Fig. 3 is a top plan view of the fastening devices for the connecting bar members, Fig. 4 is a detail perspective view of one of the clasps for holding the connecting members together.

Referring to the drawing, the numeral 1 designates the supporting members, each comprising a post of rectangular cross section, said posts or supports having a V-shaped lower end 2 and a rounded upper end 3. Braces 4 are pivotally connected upon staples 5 attached to the members 1 and adapted to be swung down into line with the supports 1 when not required for use. Shorter braces 6 are similarly connected to staples 7 at opposite sides of the supporting posts 1, and these braces are also adapted to fold inward and lie against the supporting posts 1 when not required for use.

A connecting bar, consisting of two detachable members 8 extends from the top of one of the supporting post to the other. 55 Each of the members 8 is provided with a clasp 9, comprising a metal shank having an engaging member 10 at one end thereof and a downwardly extending flange 11, as shown best in Fig. 4. Each of these clasps is pivoted at 12 to the member 8, and when it is desired to disconnect the members, the bolts 13 are removed. The bolts 13 hold the overlapping ends of the sections 8 firmly in place and are to be removed when the frame is to 60 be folded. The other ends of the members 8 are connected by means of hinges 14 to the inner sides of the supporting posts 1. Pivoted under each of the hinges 14 is a hook 15 for supporting a hammock 65 16.

From the foregoing it will be obvious that the hammock supporting frame may be quickly set up by placing the end posts in proper position and inserting the bolts 13 70 in the connecting members 8, and when not required for use, the removal of the bolts 14 will permit all of the members to fold together so that they can be packed away in a small space.

The invention is simple in construction, can be manufactured at low cost, can be quickly set up without the use of special tools and by an unskilled person, and can be folded within a small space when not required for use.

What is claimed is:—

The herein-described folding hammock supporting frame comprising upright posts, braces hinged to said posts, a sectional connecting bar hinged at its outer ends to said posts, and means for detachably connecting the inner ends of the sections of said connecting bar, said means comprising overlapping contacting clasps pivoted to said sections, and hooks connected to said posts underneath the sectional connecting bar.

In testimony whereof I affix my signature in presence of two witnesses.

BASIL L. FOGLE.
